UNITED STATES PATENT OFFICE

115,285

DESIGN FOR A TABLE OR SIMILAR ARTICLE

Robert A. Conkling, Jr., Olean, N. Y., assignor of one-half to Kenneth D. Fobes, Hollywood, Calif.

Application November 8, 1938, Serial No. 80,966

Term of patent 3½ years

To all whom it may concern:

Be it known that I, Robert A. Conkling, Jr., a citizen of the United States residing at Olean, in the county of Cattaraugus and State of New York, have invented a new, original, and ornamental Design for a Table or Similar Article, of which the following is a specification, reference being had to the accompanying drawing, forming part thereof, and in which

Figure 1 is a perspective view of a table or similar article showing my new design;

I claim:

The ornamental design for a table or similar article substantially as shown.

ROBERT A. CONKLING, JR.
